(57) **CLAIM**

The ornamental design for a strap clamp, as shown and described.

DESCRIPTION

FIG. 1 is a perspective view of the front of the strap clamp design.

FIG. 2 is a top view thereof.

FIG. 3 is a bottom view thereof.

FIG. 4 is a front view thereof, with the bolt shown in a different position than as shown in FIG. 1; and,

FIG. 5 is a side view thereof, with the bolt shown in a different position than as shown in FIG. 1 or FIG. 4.

The article in which the design is embodied is a fastener for terminating a metallic strap which holds a solar panel to a building structure such as a roof. More particularly, the ornamental design is embodied in a hollow clamp device having open sides through which a metallic strap can pass, a screw with a hex head rotatably mounted on a top portion of the device, and a slotted bottom portion having a hole formed therein.
